UNITED STATES PATENT OFFICE.

EZRA W. HASENPFUG, OF GENEVA, OHIO.

DOOR-STOP.

No. 841,147.

Specification of Letters Patent.

Patented Jan. 15, 1907.

Application filed November 29, 1904. Serial No. 234,786.

To all whom it may concern:

Be it known that I, EZRA W. HASENPFUG, a citizen of the United States of America, and a resident of Geneva, in the county of 5 Ashtabula and State of Ohio, have invented certain new and useful Improvements in Door-Stops, of which the following is a specification.

My invention relates to improvements in 10 door-stops, and has for its object the construction of a strong, cheap, and serviceable article of this class, preferably shaped from sheet-metal stampings.

My idea has been to so arrange, construct, 15 and proportion the parts as to afford a maximum strength, while permitting the device to be very easily and cheaply constructed and affording at the same time an article which will be wholly satisfactory and durable when placed in service.

The features of my invention may be at 20 once gathered by an inspection of the annexed drawings, showing in detail a device manufactured in accordance with my invention and embodying the same in a preferred form.

Referring to said drawings, Figure I shows 25 in side view a door-stop constructed in accordance with my invention. Fig. II depicts the same in longitudinal section on line II II of Fig. I. Fig. III is a view similar to Fig. I, partially broken away at the base-cap better to illustrate the construction. Fig. IV is an interior view of the base-cap, 30 indicating the supporting-screw in section. Fig. V is a plan view of the crowning-cap, and Fig. VI a vertical section thereof.

Throughout the several figures, I have designated similar parts by the same character 35 of reference to avoid any ambiguity.

Five separate parts are employed in constructing the door-stop herein shown. These 40 comprise a conical body *a*, ordinarily formed of sheet-steel, the outer end of which is crowned by the cap *c*, mounting an interiorly-flanged button *b*, of rubber or like material, against which the door or similar part abuts or is swung. The means for attaching 45 said button to the cap comprises a flanged nipple *b'*, adapted to be forced through a circular or substantially circular opening in the top of the cap and engage the inner face thereof. In Figs. V and VI are shown details of the preferred form of crowning-cap *c*, 50 which is stamped out to present a substan-

tially circular central opening, slotted upon one side, however, and having one of the points *c'* sprung inward. The opening resembles a keyhole in shape and is given this form for the purpose of permitting the rubber button *b* to be more readily inserted in and removed from said cap when desired. The flanged edge of the cap *c* in turn is compressed over the outer end of the conical or tubular body *a*, securing the parts in position 60 and holding the latter in shape. The inner end of said tubular part is provided with feet or lugs *a'*, adapted to enter segmental slots *d'* cut in the base-cap *d*, wherein they are upset and serve to unite these parts. Previous to 65 assembling the same a square-headed screw *e* is inserted in the similarly-shaped opening *d'* of the base-cap and firmly riveted or upset upon the outer face of said cap.

When constructed in accordance with the 70 foregoing description, it will be appreciated that a door-stop having such general characteristics not only is cheap and easily constructed, but that it has the more important qualities of being extremely serviceable and 75 possessing great strength. Hence the construction may be relatively light. The screw used is short and stout and is attached to the base-cap in a manner to avoid its turning 80 therein or being broken from its anchorage. 85

The mode of attaching the rubber button or stopper, of course, is optional, since well-known means may be employed therefor, and the different parts of the construction may readily be given more ornamental 90 configuration or shape in the course of stamping. The manner of uniting the several parts may also vary somewhat without departing from the essence of my invention, although as 95 thus constructed said parts contribute to the general strength and materially reinforce each other.

Having now set forth the preferred embodiment of my invention, both by drawings and description thereof, I claim as new, and 100 desire to secure by Letters Patent, the following:

1. A sheet-metal door-stop, comprising a tubular body portion seated upon a base-cap, equipped with a screw, the said body portion 105 having a crown or cap attached to its outer end, carrying a suitable button or stop, substantially as set forth.

2. In a door-stop of the class described, the combination with a substantially tubu- 110

lar sheet-metal body portion, of a cap secured about its outer end, a button or stop upon said cap having a flanged part or nipple engaging said cap, a base portion mounting the tubular body, and a screw provided upon the base portion, substantially as set forth.

3. In a stop or abutment for doors and the like, the combination with a light sheet-metal body portion or support, having an opening in its outer end or face, of a button provided with an inner flanged nipple, inserted through said opening, and engaging a support, whereby said button is securely mounted in place, substantially as set forth.

4. The herein-described sheet-metal doorstop, comprising a conical body portion, a cap clamped thereon, having a substantially circular opening, a flanged rubber button fitting therein, a base-cap mounting the body

portion, and a screw inserted and secured in said base-cap, substantially as set forth.

5. The herein-described sheet-metal doorstop, comprising a tubular body portion terminating in feet or lugs, a cap clamped upon the upper end thereof, and having a substantially circular opening, a flanged rubber button inserted therein, a base-cap receiving the lugs, wherein the same are upset, and a short screw securely riveted within the base-cap, to prevent it from turning therein, substantially as set forth.

Signed at Geneva, Ohio, this 26th day of November, 1904, in the presence of two subscribing witnesses.

EZRA W. HASENPFLUG.
